UNITED STATES PATENT OFFICE

91,863

DESIGN FOR A BEVERAGE COOLER

Thomas J. Fegley, Philadelphia, Pa., assignor to
North Bro's Mfg Co., Philadelphia, Pa., a cor-
poration of Pennsylvania

Application June 23, 1933, Serial No. 48,510

Term of patent 3½ years

To all whom it may concern:

Be it known that I, THOMAS J. FEGLEY, a citizen of the United States, residing in Philadelphia, Pennsylvania, have invented a new, original, and ornamental Design for a Beverage Cooler, of which the following is a specification, reference being had to the accompanying drawing, forming part thereof, in which

Figure 1 is a perspective view illustrating my new design for a beverage cooler, with the lid re-

Fig. 2 is a perspective view with the lid in place.

I claim:—

The ornamental design for a beverage cooler, being had to the accompanying drawing, forming substantially as shown, and described.

THOMAS J. FEGLEY.
